[57] CLAIM

The ornamental design for a football memorabilia, as shown and described.

DESCRIPTION

FIG. 1 is a side, front perspective view of a football memorabilia showing my new design;

FIG. 2 is a front view thereof;

FIG. 3 is a left side view thereof;

FIG. 4 is a rear view thereof;

FIG. 5 is a right side view thereof;

FIG. 6 is a top plan view thereof;

FIG. 7 is a bottom plan view thereof;

FIG. 8 is a side, front perspective view of a second embodiment of a football memorabilia;

FIG. 9 is a front view thereof;

FIG. 10 is a left side view thereof;

FIG. 11 is a rear view thereof;

FIG. 12 is a right side view thereof;

FIG. 13 is a top plan view thereof;

FIG. 14 is a bottom plan view thereof;

FIG. 15 is a side, front perspective view of a third embodiment of a football memorabilia;

FIG. 16 is a front view thereof;

FIG. 17 is a left side view thereof;

FIG. 18 is a rear view thereof;

FIG. 19 is a right side view thereof;

FIG. 20 is a top plan view thereof; and,

FIG. 21 is a bottom plan view thereof.

The broken line showing of a helmet and kicking tee is for illustrative purposes only and forms no part of the claimed design.
